Application December 22, 1949, Serial No. 134,423

7 Claims. (Cl. 53—7)

1

This invention pertains to the making and filling of shipping containers, particularly containers designed to hold a plurality of independent articles, for example, cans or bottles disposed in orderly rows.

In my copending application for Letters Patent, Serial No. 106,824, filed July 26, 1949, I have disclosed a novel container designed to be filled through an open side by relative movement in a substantially horizontal direction of the empty container and a filler unit, the latter comprising the articles to be placed in the container and a spacer grid which holds the articles in the desired rows. The container therein illustrated is a cardboard carton made from a single piece of sheet material so designed that it may be partially folded, then stitched while moving horizontally between stitching devices which insert fasteners into the opposite ends of the carton, and then moved to a filling station where the filler unit is introduced through the open side. The carton specifically illustrated in said application has unitary top, rear and bottom walls, and has closure flaps which collectively constitute the front wall of the closed carton, the carton being filled through its open front, after which the closure flaps are closed and usually sealed.

However, cartons partially formed in accordance with the procedure described in said application may, if desired, be so turned, after the stitching operation is completed, that the initially open closure flaps, when closed, collectively constitute either the top or bottom wall of the filled container instead of its front wall. For some uses, this arrangement is desirable, the filler unit being introduced into the empty container either through said open top or bottom, as circumstances may indicate to be most desirable.

The principal object of the present invention is to provide a novel method of making and filling containers of the class described. A further object is to provide a novel method of introducing a filler unit into a container while its closure flaps are located at the bottom. A further object is to provide a novel method of making and filling cartons wherein a carton is first made from a unitary piece of sheet material which is partially folded and then stitched while moving horizontally through a stitching zone, and subsequently filled and sealed. A further object is to provide a novel method of introducing a filler unit into a carton while the latter is inverted and for adequately supporting the filler unit during the closing operation. Other and further objects and

2

advantages of the invention will be pointed out in the following more detailed description and by reference to the accompanying drawings wherein:

5 Fig. 1 is a perspective view of a blank which may be used in the manufacture of a carton in accordance with the present invention;

Fig. 2 is a perspective view showing the same blank partially folded;

10 Fig. 3 is a vertical section, from front to rear of the partially folded blank, showing the latter mounted on a mandrel to facilitate the stitching of the end-forming members of the blank;

Fig. 4 is a perspective view showing the blank 15 with its ends folded in readiness for the performance of the stitching operation;

Fig. 5 is a perspective view of the embryo carton of Fig. 4 as it appears after the performance of the stitching operation;

20 Fig. 6 is a transverse section on the line 6—6 of Fig. 5, showing the appearance of the end wall of the container from the inside;

Fig. 7 is a perspective view of the filled carton, with its closure flaps at the top;

25 Fig. 8 is a perspective view of a filler unit;

Fig. 9 is a fragmentary diagrammatic plan view of apparatus useful in the filling and closing of a carton in accordance with the present invention;

Fig. 10^a is a fragmentary diagrammatic view showing some of the mechanism which appears at the left-hand portion of Fig. 10, but illustrating a modified form of carton;

35 Fig. 11 is a fragmentary elevation, similar to Fig. 10, but showing a filler unit as having been inserted in the carton;

Fig. 12 is a fragmentary elevation showing a 40 further step in the closing of the carton;

Fig. 13 is a fragmentary elevation illustrating a still further step in the closing operation;

Fig. 14 is a perspective view of a carton of modified construction;

45 Fig. 15 is a plan view of a blank useful in making the carton of Fig. 14;

Fig. 16 is a perspective view illustrating a carton of still further modified construction; and

50 Fig. 17 is a plan view of a blank useful in making the carton of Fig. 16.

The practice of the present invention results in the production of a filled rectangular carton made of sheet material such as cardboard. As here illustrated, a spacer grid, also usually of cardboard, is disposed within the carton, and in

each cell or compartment of the grid there is an article, for example, a bottle. During the earlier stages of forming the carton the filling opening is at one side but prior to filling the carton is turned so that the filling opening is at the bottom. The carton is made from a unitary blank of the selected sheet material which is scored and slit to facilitate folding and to define the top, bottom and rear walls, closing flaps and end-forming and uniting tabs. One such blank is illustrated by way of example in Fig. 1.

According to one embodiment of the invention the carton, after completion, but before filling and with its filling opening at the front, appears as illustrated in Fig. 5. This carton comprises single thickness unitary walls front and rear 20 and 21 (Fig. 3) integrally joined to a wall 22 which may constitute the top during the filling operation, but which, after filling, may and usually does form the one piece, permanently closed bottom of the filled and sealed carton. The front and rear walls 20 and 21 are joined along transverse edges to the wall 22 at the front and rear, respectively, of the latter. Main, top closure flaps 23 and 24 are integrally joined at parallel fold lines to the other transverse edges of the walls 21 and 20, respectively; end-forming tabs 27 and 28 (Fig. 2) are integrally joined to the lateral edges of the wall 20; end-forming tabs 25 and 26 (Fig. 2) are integrally joined to the lateral edges of the wall 22; and other end-forming tabs 29 and 30 (Fig. 4) are integrally joined to the lateral edges of the wall 21. Auxiliary top closure flaps 31 and 32 are also integrally joined along fold lines to the transverse rear edges of the end closure tabs 29 and 30, respectively.

When the carton is first set up (Fig. 4) the end forming tabs 27 and 29 are vertical, and in overlapping relation. If the blank is exactly like that shown in Fig. 1, the tabs 27 and 29 will overlap each other, and likewise the end forming tabs 28 and 30. However, if the tabs 27 and 29 and 28 and 30 are of lesser dimensions than shown in Fig. 1, they may not overlap. In any event the end forming tabs 27 and 29 will overlap the end forming tab 25, and end forming tabs 28 and 30 will overlap the end forming tab 26. The tabs 28 and 30 are also vertical, and in overlapping relation. The end forming tabs 25 and 26 are also vertical, at right angles to the top wall 22 and overlapped by the end forming tabs 27 and 29, and 28 and 30, respectively, as just noted. Penetrating fasteners 33 (Fig. 5) (herein termed "stitches"), usually wire staples, unite the overlapped end-forming tabs, the combined tabs 25, 27 and 29 forming one end wall, and the tabs 26, 28 and 30 forming the other end wall of the carton. The amount of overlap of these end-forming tabs will vary according to the particular style of carton. While penetrating fasteners are preferably employed, it is contemplated that adhesive fastening means may be used within the broader aspects of the invention. After the carton has been set up and filled, the main closure flaps 23 and 24 are folded in to lie parallel to the top wall 22; the auxiliary end closure flaps 31 and 32 likewise being folded to lie parallel to the wall 22, and the several closure flaps are united by adhesive or other fastening means, thus completing the filled container.

Assuming that blanks B (Fig. 1) properly dimensioned, scored and slit have been prepared, a supply of such blanks may be stacked in a suitable magazine, and from this magazine the blanks are drawn one at a time in succession,

either by hand or mechanically. Initially the blank is flat and horizontal, being supported in this horizontal position by any suitable means, for example, by an elongate table top or bench, or by the upper run of a conveyor. The blank is first moved to a station where it remains for a sufficient interval of time to permit the first folding operation whereby the wall 22 is first disposed vertically and the walls 20 and 21 are disposed horizontally and spaced apart by the width of the wall 22. The result of this folding operation is illustrated in Fig. 2. At this time the main closure flaps 23 and 24 are horizontal and disposed in the same planes as the walls 21 and 20, respectively. At this time the tabs 25 and 26 are vertical, lying in the same plane as the wall 22, while the end closure tabs 27, 28, 29 and 30, and the auxiliary flaps 31 and 32 are horizontal. This partially folded blank or embryo carton is now moved horizontally to an end-folding station where a mandrel 54 (Fig. 3) is introduced, either by hand or mechanically, into the embryo carton, moving in the direction of the arrow E (Fig. 3) until it contacts the inner surface of the wall 22. The end closure tabs 25 and 26 are now turned in so as to stand at right angles to the wall 22 and the end closure tabs 27, 29 and 28, 30 are turned to lie in vertical planes and so that they overlap the end closure tabs 25 and 26. This folding operation may be carried out manually or automatically. The result of this folding operation is illustrated in Fig. 4, the embryo carton now being set up and its ends being closed in readiness to be stitched. The mandrel 54 has an external contour and dimensions like those of the interior of the carton to be made. Each side wall of the mandrel has a hard wear-resistant anvil, if staples are used as the fastening elements. The mandrel is now further advanced and by pressure against the wall 22 moves the embryo carton into a stitching zone. The advance of the carton through this stitching zone is intermittent or step-by-step. In passing through this zone, penetrating fasteners 33, for example wire staples, are inserted at each step of the intermittent movement of the carton so as to unite the end closure tabs 27 and 29 to the end closure tab 25 and the end closure tabs 28 and 30 to the end closure tab 26. These staples are clenched against the wear-resistant surfaces of the mandrel 54.

As suggested, these fasteners are preferably work-penetrating elements such as staples, rivets or other type of metallic fastener; however, they may be sewing stitches and they may be introduced by hand or machine. On the other hand, non-penetrating fastener means, such as adhesive, may be employed. Conveniently, if staples are to be inserted by a machine, a staple-inserting mechanism of any appropriate kind is arranged at each side of the path of movement of the carton as the latter is advanced through the stitching zone, each fastener inserting mechanism being so designed as to insert a fastener into the overlapping end-forming tabs of the carton at one end respectively of the latter. The result of this fastener inserting operation is indicated in Fig. 5, the carton being shown as having four staples in each side. However, a greater or lesser number of staples may be inserted if desired. At the completion of this operation, the closure flaps 23 and 24 are still in the horizontal position. After the last staples have been inserted, the embryo carton is advanced in any desired way to the filling or loading station. However, on its

way to the filling or loading station, it is so turned, either mechanically or by hand, that the wall 22 is uppermost, the carton being inverted and having its filling opening at the bottom during the filling operation.

At the loading station (Fig. 10), the main, rear closure flap 23 remains in the vertical plane of the wall 21, the auxiliary closure flaps 31 and 32 are turned outwardly (Fig. 9) to lie in a horizontal plane, and the front main closure flap 24 is also turned outwardly to lie in the same horizontal plane, thus leaving the bottom opening wide open. Any appropriate means may be employed for holding the carton in this inverted position with the flaps 24, 31 and 32 horizontal.

At the filling station a load or filler unit is introduced into the carton. As here illustrated by way of example, but without limiting intent, this load or filler unit 63 (Fig. 8) comprises a spacer grid consisting of transversely and longitudinally extending interlocked members of stiff sheet material, for example, cardboard, arranged to provide a plurality of pockets or cells, each of such dimension as to be capable of receiving one of the articles 66, for example, a bottle, which is to be packaged. This grid member is preferably of such horizontal dimensions as to fit snugly within the carton.

The filler unit 63 is prepared in readiness for introduction into the empty carton in any desired way, for example, by hand or mechanically. The articles 66 may be supplied by conveyor means and are delivered to provide the desired number of rows of articles to form a filler "block" comprising articles in number sufficient to fill each cell of the spacer grid. This block of articles is arranged upon a suitable support or elevator having provision for moving it up and down, this elevator being located directly beneath and in registry with the empty carton at the loading station. The spacer grid may be placed by hand within the empty carton before the latter is inverted, provided the grid be of such dimensions as to fit snugly in the carton. Alternatively the grid may be supported in the path of the rising block of articles so as to receive one article in each of the cells as the elevator rises. The elevator, with its block of articles, dwells in elevated position while holding the articles within the grid cells, and while it is so dwelling, the inverted carton with the filler unit within it is moved horizontally off of the elevator. As it is being pushed off of the elevator, the downwardly depending closure flap 23 is swung up to horizontal position where it underlies the filler unit. As the carton continues to move in the same direction, the closure flap 24 is swung through an arc of 180°, the supports S, hereafter referred to, being withdrawn laterally to permit this movement of the flap. At the end of this movement, both closure flaps 23 and 24 are horizontal and underlie the filler unit.

The forward horizontal movement of the carton is continued, and during this movement glue is applied to the under surfaces of the auxiliary closure flaps 31 and 32, and each of these flaps is then turned through an angle of 180° so as to underlie the closed flaps 23 and 24. The carton may now be subjected to pressure or suitably confined so as to keep the auxiliary flaps 31 and 32 in contact with the main closure flaps 23 and 24 until the glue has set. The filled and closed carton may now be stored or shipped; usually it will be inverted so that the wall 22 becomes

the bottom wall before it is stored or shipped.

By way of example, apparatus useful in filling and closing the container is diagrammatically illustrated in Figs. 9 to 12, inclusive. As shown in Fig. 10, bottles 66 are being delivered by a conveyor 67 to an elevator 70. When sufficient bottles to fill the carton have been deposited upon the elevator, the further advance of bottles is stopped in any suitable way, for example, by means of a rigid baffle plate or guard G depending from the elevator and which, as the elevator begins to rise, blocks the path of advance of the bottles. As illustrated in Fig. 10, horizontal grid-supporting elements W may be provided, these supporting elements being placed directly above the elevator and on these supporting elements the grid is placed so that one of the bottles enters each grid cell as the elevator rises. Assuming that the empty carton has been inverted over the grid and is thus directly above the elevator, as shown in Fig. 10, the elevator is caused to rise, thus lifting the block of bottles until one bottle has been entered into each cell of the grid, as shown in Fig. 11. The elevator dwells in this position while a pusher 71 engages the left-hand or front wall of the carton and pushes the latter horizontally from off the elevator. To the right of the position of the empty carton (as shown in Fig. 10) there are arranged two thin, horizontal blade-like supports S and S' (Fig. 9) whose upper surfaces are disposed in a horizontal plane preferably slightly below that of the upper surface of the elevator when the latter is in its highest position. These blade-like supports S and S' are capable of movement in opposite directions transversely of the direction of movement of the pusher 71. As the pusher 71 begins its movement to the right, these supports S and S' occupy their proximate, relative positions shown in Fig. 9, and as the filled carton starts to advance horizontally, its right-hand portion begins to ride up onto the supports S and S', the left-hand edges of which engage the downwardly directed closure flap 23 and cause the latter to swing upwardly as shown in Fig. 11, so that eventually it becomes horizontal, underlying the filler unit within the carton. While the elevator still dwells in its upper position, the pusher 71 continues to move the carton in this direction until the carton is above the members S and S', whereupon the elevator descends.

As here shown, by way of example, the pusher carries a transverse, rotatable shaft 72 (Fig. 9) provided at its opposite ends with segmental pinions 73 which engage fixed horizontal bars Q provided, at the areas H, with rack teeth so that, as the pusher advances to the right, the pinions are brought into mesh with the teeth and the shaft 72 is partially rotated. A flap-turning arm 75 is secured to the central part of the shaft 72. This arm 75 is horizontal and overlies the front closure flap 24 when the parts occupy the position shown in Fig. 10, but as the pusher advances to the right, this arm 75 begins to turn, and, by contact with the flap 24, swings the latter through an arc such that the free margin of the flap 24 underlies the thin, blade-like supports S and S', as shown in Fig. 12. The advancing lower edge of the carton now begins to ride up onto a stationary elongate table T and the supports S and S' begin to move away from each other, thus providing space between their proximate edges for the main closure flap 24. The table T has a downwardly inclined

finger F which contacts the free edge of the flap 24 as the carton is further moved to the right, thus completing the upswing of the flap 24 to a horizontal position where it underlies the filler unit within the carton. As soon as the edge 5 of the flap 24 contacts the finger F, the pusher 71 returns to its initial position and further motion of the carton is occasioned by bars Z carried by endless chains Y or equivalent means. During advance of the carton along the table 10 T, the auxiliary closure flaps 31 and 32 pass over the surfaces of glue coated rolls R which apply adhesive to the under surfaces of the flaps. The auxiliary flaps 31 and 32 then engage fixed turning scrolls C which, as the carton continues to advance toward the right, turn the flaps through arcs of 180° so that they underlie the closed main closure flaps 23 and 24. The bars Z move the carton along until it slides off of the table T and onto a conveyor K. During 20 this final motion, the carton may be subjected to pressure, for example, by a pressure roll (not shown) so as to hold the auxiliary flaps 31 and 32 in contact with the flaps 23 and 24 until the adhesive has set. The filled carton is then 25 usually turned so that the closure flaps are at the top, as shown in Fig. 7.

In Fig. 10^a a carton K, similar to that illustrated in the aforementioned copending application Serial No. 106,824, is shown in inverted position to receive a filler unit which is moved upwardly into the carton. The carton is disposed with the flap 23^x in substantially vertical position and with the flap 24^x bent outwardly and horizontally. In this instance the flap 23^x has integral sealing tabs 31^x and 32^x which are bent to lie in parallel planes at right angles to the main portion of the flap 23^x. As the flap 23^x is swung upwardly into closing position during the movement of the carton, through the several positions illustrated in Figs. 11, 12 and 13, the sealing tabs 31^x and 32^x enter the carton between the side walls of the latter and the filler unit. Adhesive may be applied to these sealing tabs 31^x and 32^x before the part 23^x is folded up, so as to unite the sealing tabs 31^x and 32^x to the carton wall.

In Fig. 14 a carton of slightly modified form is illustrated, capable of being made, filled and closed in substantial accordance with the method hereinbefore described. This carton is made from the blank shown in Fig. 15 wherein parts corresponding to those of the blank of Fig. 1 are similarly designated.

The carton shown in Fig. 14 is wider in proportion to its height than the carton formed from the blank of Fig. 1 so that, when set up, the end closure tabs 27 and 29 do not overlap but have their vertical edges in abutting relation, the same being true of the end closure tabs 28 and 30. In this blank, the end closure tabs 29 and 30 have the auxiliary closure flaps 31 and 32 integrally joined to their transverse edges, as in Fig. 1, but in this blank the tabs 27 and 28 likewise have auxiliary closure flaps 31^a and 32^a. During the stitching operation staples 33 (Fig. 14) are driven through the end closure tabs 27 and 29 into the end closure tab 25 at one end of the carton, and at the other end staples are driven through the end closure tabs 28 and 30 into the end closure tab 26, as previously described, but the stitching operation is continued so as to unite the proximate edges of the auxiliary closure flaps 31 and 31^a and 32 and 32^a respectively. The united auxiliary closure flaps

31 and 31^a and 32 and 32^a now constitute the end closure flaps. After the stitching operation, which is performed with the wall 22 of the carton disposed vertically, the carton is turned as above described so that its open side is now at the bottom and the filling and closing operation is carried out as above described. While it is preferred to unite the adjacent edges of the auxiliary closure flaps 32 and 32^a and 31 and 31^a as above suggested, this is not essential and these flaps at each end may be left free from each other.

In Fig. 16 a further modification is illustrated wherein the carton is quite shallow as compared with its horizontal dimensions. This carton may be made from a blank such as shown in Fig. 17 and filled and closed in substantial accordance with the method above described. In Fig. 17 parts of the blank corresponding to those of the blank of Fig. 15 are similarly designated. The blank is substantially like that of Fig. 15 except for relative difference in the size of parts and that the auxiliary closure flaps 31, 32, 31^a and 32^a are omitted and tabs 25 and 26 have auxiliary closure flaps 25^a and 26^a at their lateral edges.

In setting up this blank, the wall 22 is vertically disposed, as above described, the walls 20 and 21 being horizontal, the longer dimensions of the tabs 25 and 26 being vertical. During the stitching operation the auxiliary closure flaps 25^a and 26^a lie in the same planes as the tabs 25 and 26 respectively. Because the tabs 27, 28, 29 and 30 are quite narrow as compared with the lengths of the tabs 25 and 26, it is necessary to employ two rows of stitches 33 in forming the end walls of the carton, one row of stitches uniting the tabs 25 and 29 and another row uniting the tabs 25 and 21 at one end of the carton, while at the other end one row of stitches unites the tabs 28 and 26 and the other unites the tabs 30 and 25. If the fasteners are inserted by machine it may be necessary to employ two fastener-inserting devices, one above the other at each side of the path of travel of the carton through the stitching zone. Alternatively the carton may be fed through the stitching zone while inserting one row of fasteners at each end, and then retracted, turned upside down and again fed through the stitching zone to insert the other row of fasteners at each end.

After stitching, the carton is inverted, the closing flaps and end-forming tabs are arranged as above described in respect to the carton of Fig. 1, the filler unit is inserted by upward movement through the bottom opening of the carton, and the flaps and tabs are closed and secured.

While for convenience reference has herein been made to "front," "rear" and "end walls," these terms are used merely for clarity in description and without limiting intent. Likewise while in describing apparatus for use in filling and closing the carton certain specific descriptive terms have been used, it is to be understood that these are merely suggestive of any equivalent parts, elements or devices appropriate for the performance of the desired function, and while one desirable type of mechanism has been shown for use in performing the filling and closing operations, it is to be understood that this apparatus is merely by way of example and that other apparatus may be employed, or that the several operations may be carried out by hand.

While certain desirable embodiments of the invention have been herein specifically illustrated by way of example, it is to be understood that the invention is broadly inclusive of any and all

modifications falling within the scope of the appended claims.

I claim:

1. That method of making a package including a carton of stiff sheet material and a filler housed within the carton, the filler including a plurality of independent articles disposed within the respective cells of a spacer grid, said method comprising as steps providing a substantially rigid, rectangular carton having front, rear and side walls, which is permanently closed at its bottom but open at its top and provided at its top with main closure flaps hinged to its front and rear walls, respectively and auxiliary closure flaps hinged to its opposite side walls, respectively, providing a spacer grid, placing the spacer grid within the carton, inverting the carton while disposing its closure flaps so as to leave the top of the carton completely open, assembling the required number of articles in orderly rows to form a block, raising the block of articles so as to introduce one of the articles into each cell of the grid, the upward movement being continued until the bottom of the block of articles is substantially level with the edge of the top of the inverted carton, and advancing the carton, together with the filler horizontally uninterruptedly along a rectilinear path perpendicular to the hinge joint between its rear wall and the closure flap attached thereto while closing and fastening the main and auxiliary closure flaps.

2. That method of filling a container having front and rear walls, a permanently closed bottom, end walls, main closure flaps integrally joined to the transverse edges of the front and rear walls, and auxiliary closure flaps integrally joined to elements of the end walls, said method comprising as steps arranging the container with its bottom wall uppermost and substantially horizontal, disposing the rear main closure flap in a depending position, turning the front main closure flap and the auxiliary closure flaps outwardly so as to leave the top of the carton completely open, elevating a filler unit thereby to introduce the filler unit into the container, and, while uninterruptedly moving the container with its rear wall in advance, with the filler unit, along a rectilinear horizontal path which is perpendicular to the line of junction between the main rear closure flap and the rear wall, turning the main rear flap upwardly so as to underlie the filler unit, then turning the main front closure flap to underlie the filler unit, and while continuing to advance the container along the same rectilinear path, applying adhesive to the auxiliary closure flaps, turning the auxiliary closure flaps to underlie the main closure flaps, and subjecting the container to pressure until the adhesive has set and united the several flaps.

3. That method of making a filled shipping container which comprises as steps providing a substantially rigid one-piece container of sheet material having front, rear, bottom and end walls, main top closure flaps integrally joined to the top edges of the front and rear walls respectively, and auxiliary top closure flaps integrally joined to the top edges of the respective end walls, inverting the container and so disposing it that its front and rear walls are vertical with its bottom wall uppermost, disposing the main closure flap which is connected to the rear wall in a substantially vertical plane, turning the main closure flap which is connected to the front wall and also the auxiliary closure flaps outwardly to lie in a substantially hori-

zontal plane, thereby leaving the top of the container completely open, disposing a filler unit below and in registry with the container, moving the filler unit upwardly into the container, and, while supporting the filler unit within the inverted container, uninterruptedly advancing the container along a rectilinear horizontal path perpendicular to the junction of its rear wall with the closure flap which is attached thereto while closing the main and auxiliary closure flaps and uniting the closed flaps.

4. That method of making a filled shipping container which comprises as steps providing a substantially rigid one-piece container of sheet material having front, rear, bottom and end walls, main top closure flaps integrally joined and hinged to the top edges of the front and rear walls respectively, and auxiliary top closure flaps integrally joined to the top edges of the respective end walls, inverting the container and so disposing it that its front and rear walls are vertical with its bottom wall uppermost, disposing the main closure flap which is connected to the rear wall in a substantially vertical plane, turning the main closure flap which is connected to the front wall and also the auxiliary closure flaps outwardly to lie in a substantially horizontal plane, thereby leaving the top of the container completely open, providing a filler unit including a spacer grid, moving the filler unit upwardly into the container, uninterruptedly advancing the container along a rectilinear horizontal path substantially perpendicular to the hinge joint between the rear wall and the closure flap which is attached thereto while concomitantly swinging the main closure flap attached to the rear wall to a horizontal position where it underlies the filler unit, then swinging the main closure flap which is attached to the front wall until it underlies the filler unit, continuing the advance of the container along said rectilinear path while turning the auxiliary closure flaps to underlie the main closure flaps, and submitting the container to pressure while adhesively bonding the closed main and auxiliary flaps.

5. That method of making a filled shipping container which comprises as steps providing a substantially rigid one-piece container of sheet material having front, rear, bottom and end walls, main top closure flaps integrally joined and hinged to the top edges of the front and rear walls respectively, and auxiliary top closure flaps integrally joined to the top edges of the respective end walls, inverting the container and so disposing it that its front and rear walls are vertical with its bottom wall uppermost, disposing the main closure flap which is connected to the rear wall in a substantially vertical plane, turning the main closure flap which is connected to the front wall, and also the auxiliary closure flaps, outwardly to lie in a substantially horizontal plane, thereby leaving the top of the container completely open, providing a filler unit, moving the filler unit upwardly into the container, advancing the container with the filler unit uninterruptedly along a horizontal rectilinear path substantially perpendicular to the hinge line between the rear wall and the closure flap which is attached thereto while that downwardly directed main closure flap which is attached to the rear wall is swung so that its free edge underlies the filler unit, continuing to advance the container along the same rectilinear path while swinging that main closure flap which is attached to the front wall until its free edge underlies the filler

11

unit, and while continuing to advance the container along the same rectilinear path, applying adhesive to the under surfaces of the horizontally disposed auxiliary closure flaps, swinging said auxiliary closure flaps to underlie the main closure flaps and applying pressure to the container to unite the adhesively coated auxiliary closure flaps to the main closure flaps.

6. That method of making a filled shipping container which comprises as steps providing a substantially rigid, rectangular one-piece container of sheet material having front, rear, bottom and end walls, main top closure flaps integrally joined and hinged to the top edges of the front and rear walls respectively, and auxiliary top closure flaps integrally joined to the top edges of the respective end walls, inverting the edges of the respective end walls, inverting the container and so disposing it that its bottom wall is uppermost and horizontal, and with its closure flaps so disposed as to leave the top of the container completely open, moving a filler unit upward and into the container, and while uninterruptedly advancing the container along a rectilinear path substantially perpendicular to the hinge joint between the rear wall and the closure flap which is attached thereto, moving the main closure flaps to underlie the filler unit, turning the auxiliary closure flaps to closed position and uniting the main and auxiliary closure flaps.

7. That method of making a filled shipping container which comprises as steps providing a substantially rigid one-piece container of sheet material having front, rear, bottom and end walls, main top closure flaps integrally joined

and hinged to the top edges of the front and rear walls respectively, and auxiliary top closure flaps integrally joined to the top edges of the respective end walls, inverting the container and so disposing it that its bottom wall is uppermost and substantially horizontal, and with its closure flaps so disposed as to leave the top of the container completely open, elevating a filler unit to introduce the filler unit into the container, advancing the filler and container uninterruptedly along a horizontal rectilinear path perpendicular to the hinge line at which the rear wall and its closure flap are united while successively swinging the two main closure flaps upwardly to underlie the filler unit, turning the auxiliary flaps to closed position and uniting the main and auxiliary flaps.
